His Attorney.

UNITED STATES PATENT OFFICE.

JOHN EATON, OF SCHENECTADY, NEW YORK, ASSIGNOR TO GENERAL ELECTRIC COMPANY, A CORPORATION OF NEW YORK.

NORMALLY-CLOSED SWITCH.

Application filed April 12, 1920. Serial No. 373,062.

To all whom it may concern:

Be it known that I, JOHN EATON, a subject of the King of Great Britain, residing at Schenectady, in the county of Schenectady, State of New York, have invented certain new and useful Improvements in Normally-Closed Switches, of which the following is a specification.

My invention relates to switches which are biased to the closed position and particularly switches which are biased to the closed position by the action of gravity.

One of the objects of my invention is to provide an improved switch of this character which will not open its contacts in response to the rebound of the gravity operated means which effects the closing of the switch contacts, or in response to shocks or jolts. Another object of my invention is to provide an improved switch of this character in which the switch contacts shall have a wiping action in closing and in the closed position the contacts shall have a spring pressure applied which will maintain the contacts closed.

A further object of my invention is to provide an electromagnet switch of the normally closed type in which the electromagnet which is provided for effecting the opening of the switch contacts is used to set up a magnetic flux which will extinguish the arc formed between the switch contacts in opening.

For a better understanding of my invention reference is had to the accompanying drawings in which I have illustrated one form of my invention in concrete form for purposes of illustration, and in which Figure 1 is a front view of an electromagnet switch embodying my invention, with the outside cover removed and the switch contacts in the closed position; Fig. 2 is a side view showing certain of the parts in section; Fig. 3 is a fragmentary view of the switch operating mechanism with the switch contacts in open position; and Fig. 4 is a simplified diagram illustrating one of the uses of my invention.

Referring to the drawings, the parts of the switch mechanism are enclosed and supported within a casing 10 of magnetic material. The stationary switch contact 11 is secured to and insulated from the casing 10, and the resiliently mounted movable switch contact 12 is secured to the end of

the lever 13 which is pivoted to the casing at 14. The movable contact 12 is secured to the lever 13 by means of the bolt 15 and is insulated from the lever by means of the tubes of insulating material 16. The 60 electromagnet which is provided for opening the switch contacts comprises a winding 17 and a plunger 18, which serves as a movable actuating member for effecting the opening and closing of the switch contacts. The lower end of the plunger 18 is slotted as shown in Figs. 2 and 3. A pin 19 which passes through the end of the plunger 18 is adapted to engage the lever 13 so as to move the lever and thereby open 65 the switch contacts when the winding 17 is energized and the plunger drawn upward within the winding. A link 20 pivotally connected to the casing 10 at 21 and also pivotally connected with the plunger 18 at 22 is provided for applying spring pressure to the contacts in closing. The spring 23 connects the lever 13 with the lever or link 20. A post 24 with a screw-thread on the end is pivoted for securing the cover of 70 the casing in place.

As thus constructed and arranged, the operation of my invention is as follows: Assume that the various parts are in position as shown in Figs. 1 and 2, that is, that the switch contacts 11 and 12 are closed and that it is desired to open the contacts and deenergize the translating device 25 controlled by the switch. The pilot switch 26 will first be closed, thereby energizing the 75 winding 17 of the electromagnet from the source of supply 27. The plunger 18 will at once be drawn upward, but the initial movement of the plunger has no effect whatsoever on the opening of the switch contacts, since the plunger must travel a certain distance before the pin 19 will engage the lever 13. This is very advantageous, because the plunger 18 has a considerable travel and the pull on the plunger is the 80 least in its lowermost position. The plunger is therefore not required to do any work in opening the contacts until after it has been drawn within the winding 17 for an appreciable distance. The lever or link 20 will of course be rotated about the pivot 21, since its righthand end is connected at 85 22 in the slot in the end of the plunger. The counter-clockwise movement of the link 20 merely releases the compression on the 90

spring 23, but does not effect the opening of the switch contacts. When the pin 19 strikes the lever 13, the lever 13 will be rotated clockwise about its pivot 14 and the 5 movable contact 12 will first slide upward a small distance along the stationary contact 11 before it leaves the stationary contact at an angle in response to the further movement of the plunger 18 within the magnet winding 17, the resiliency of the support 10 for the contact 12 permitting this contact to first slide upward before breaking engagement with the contact 11. In the final upper position of the plunger 18 the various 15 parts will be in their respective positions as shown in Fig. 3. It will be observed that the contact 12 has been moved through a more limited range of movement than the range of movement of the plunger and that 20 in the upper position the spring 23 has been again compressed so that the compression of this spring is present to assist the force of gravity in closing the switch contacts when the winding 17 is deenergized. It 25 will also be observed that the stationary contact 11 is at such a position that it is in the path of the lines of flux set up by the magnet winding 17 so that the arc formed between the two contacts when the contacts 30 open is extinguished by the flux of the winding.

With the switch in open position and the parts in their positions shown in Fig. 3, if the magnet winding is deenergized the 35 plunger 18 will at once drop and the pressure of the spring 23 will assist the force of gravity in the initial downward movement of the plunger. The lever 13 will be permitted to drop, rotating counter-clockwise about its pivotal support 14. The 40 movable contact 12 will be rotated counter-clockwise through a limited angular distance and will come into engagement with the stationary contact 11 at about the same time that the pin 19 is ready to drop free of the lever 13. At this time the link 20 is 45 ready to apply spring pressure to the contacts through the spring 23. The plunger will drop to its lower position (that shown 50 on Fig. 1), and in the final movement of the plunger the contact 12 will slide along the stationary contact 11, thereby giving a wiping action to the contacts in closing. The contacts will be maintained closed by the 55 weight of the plunger 18 acting through the link 20 and the spring 23. In the final position 60 of the plunger the spring 23 is compressed so as to apply considerable spring pressure to the contacts, and this spring also 65 serve to cushion the fall of the plunger. It will be observed that although the plunger is very apt to rebound after it has fallen to its lowest position, nevertheless the switch contacts will not be in any way affected by 70 the rebound of the plunger, since the 75

plunger will never rebound to the extent that the pin 19 will engage with the lever 13. It will also be observed that by reason of the position of the parts and from the fact that the plunger has moved through a greater 70 range of movement than the range of movement of the contact 12, the plunger acting through the link 20 will apply considerable spring pressure to the switch contacts and the contacts will not be jarred open. 75

It will be apparent from the above description that I have provided an electro-magnetically operated normally closed switch in which the rebound of the plunger of the electromagnet does not effect the 80 opening of the switch contacts, also that the switch contacts are given a wiping action in closing and in opening, that considerable spring pressure is applied to the switch contacts in the closed position, and that the 85 contacts are set up by the opening of the switch contacts is quickly disrupted by the magnetic flux of the operating electromagnet.

What I claim as new and desire to secure by Letters Patent of the United States, is:—

1. A switch of the normally closed type comprising a rigid switch contact and a cooperating movable contact, an actuating member for the movable contact biased to 90 a position at which the contacts are closed, and connections between the actuating member and the said movable contact whereby the movement of the actuating member to its biased position moves the said contact 95 angularly into engagement with the rigid contact and then gives the contacts a wiping action, the said connections arranged to permit the contacts to be maintained closed during the rebound of the actuating member. 100

2. A switch of the normally closed type comprising a pair of relatively movable switch contacts, an actuating member therefor biased to a position at which the contacts are closed, and connections between the actuating member and one of said contacts whereby the movement of the actuating member to its biased position moves the said contact angularly into engagement with the other contact and then increases the pressure between the contacts, the said connections arranged to permit pressure between the contacts to be maintained during 110 the rebound of the actuating member. 115

3. A switch of the normally closed type comprising a rigid switch contact and a cooperating movable contact, an actuating member for the movable contact held in a position at which the contacts are opened against its bias due to gravity to a position at which the contacts are closed, and connections between the actuating member and the said movable contact whereby upon the release of the actuating member the said 120 125 130

contact is moved angularly into engagement with the rigid contact and then slid along the said rigid contact as pressure is applied between the contacts.

5 4. A switch of the normally closed type comprising a stationary rigid switch contact, a movable switch contact, an actuating member therefor operated by gravity to close the contacts, and connections between the actuating member and the movable contact whereby the movable contact is moved angularly into engagement with the stationary contact and then given a wiping action with the stationary contact as pressure is applied and maintained to the contacts.

5 5. A switch of the normally closed type comprising a rigid switch contact and a cooperating switch contact movable through a limited distance into engagement with the said rigid contact, an actuating member for the said movable contact biased to a position at which the contacts are closed, the said actuating member having a greater range of movement than the range of movement of the said movable switch contact, and connections between the actuating member and the said movable contact whereby the movable contact is moved into engagement with the rigid contact during the initial movement of the actuating member and spring pressure is applied to the contacts as the actuating member completes its movement.

35 6. A switch of the normally closed type comprising a stationary switch contact, a movable switch contact, an actuating member therefor operated by gravity to close the contacts, the said actuating member having a predetermined range of movement, and connections between the actuating member and the movable contact whereby the initial movement of the actuating member moves the movable contact through a more limited range of movement and increasing spring pressure is applied to the contacts as the actuating member completes its movement to the one end of its range of movement.

50 7. A switch of the normally closed type comprising a pair of switch contacts, an actuating member therefor held in a position at which the contacts are opened against its bias due to gravity to a position at which the contacts are closed, and a system of levers connecting the actuating member with one of the switch contacts, whereby upon the release of the actuating member the contacts are closed by the initial movement of the actuating member and the pressure between the contacts is increased by the continuation of the movement of the actuating member.

8. A switch of the normally closed type comprising a stationary switch contact, a

movable switch contact, an actuating member therefor biased to one position at which the contacts are closed and movable against its bias to a second position at which the contacts are opened, a spring interposed between the actuating member and the movable contact, and connections whereby the spring is put under strain to apply pressure to the contacts in the first position of the actuating member and is put under strain in the second position of the actuating member to assist the bias of the same to the first position.

9. A switch of the normally closed type comprising a pair of switch contacts, an electromagnet having a movable actuating member therefor, the said actuating member biased to a position in which the switch contacts are closed and movable against its bias to open the contacts in response to the energization of the magnet winding, and connections whereby the initial movement of the actuating member to its biased position closes the contacts, the final movement of the actuating member applies spring pressure to the contacts, and the contacts are maintained closed during the rebound of the actuating member.

10. A switch of the normally closed type comprising a stationary switch contact, a movable switch contact, an electromagnet having a movable actuating member therefor, the said actuating member biased to a position in which the switch contacts are closed and movable against its bias to open the contacts in response to the energization of the magnet winding, and means comprising a plurality of cooperating levers connecting the actuating member with the movable switch contact, whereby the contacts are given a wiping action in closing, spring pressure is applied to the contacts in the closed position, and the contacts are maintained closed during the rebound of the actuating member.

11. A switch of the normally closed type comprising a stationary switch contact, a movable switch contact, an electromagnet having a movable actuating member therefor, the said actuating member biased by gravity to a position in which the switch contacts are closed and movable against its bias to open the contacts in response to the energization of the magnet winding, a lever pivoted at one end of a stationary support, having the movable contact secured to the other end thereof and acted upon by the actuating member of the electromagnet, a lever having one end pivoted to the actuating member and the other end pivoted to the stationary support, and a resilient connection between the two levers, whereby the contacts are given a wiping action in closing, spring pressure is applied to the contacts in the closed position, and the contacts

are maintained closed during the rebound of the actuating member.

12. In a switch comprising relatively movable contacts, a member carrying one of said contacts, an actuating member for the said contact-carrying member biased to a position in which the contacts are closed and adapted to be actuated against the bias thereof to open the said contacts, a spring through which pressure is applied to the said contacts by the actuating member when the actuating member is in its biased position and which is connected to

assist the movement of the actuating member toward its biased position, and a loose connection between the actuating member and the contact-carrying member arranged to permit a predetermined movement of the actuating member away from its biased position after the said contacts are in engagement, whereby a rebound of the actuating member will not be transmitted to the contact-carrying member.

In witness whereof, I have hereunto set my hand this 10th day of April, 1920.

JOHN EATON.
